UNITED STATES PATENT OFFICE

172,106

HANDWHEEL FOR A RAILWAY HANDBRAKE

Arthur F. O'Connor, Chicago, and Gust J.
Christenson, Park Ridge, Ill.

Application October 19, 1953, Serial No. 27,228

Term of patent 7 years

(Cl. D66—2)

To all whom it may concern:

Be it known that we, Arthur F. O'Connor and Gust J. Christenson, citizens of the United States, and residents, respectively, of Chicago, county of Cook, State of Illinois; and Park Ridge, county of Cook, State of Illinois, have invented a new, original, and ornamental Design for Handwheel for a Railway Handbrake, of which the following is a specification, reference being had to the accompanying drawing, forming a part thereof in which:

Figure 1 is a front elevational of a handwheel for a railway handbrake, embodying our new design;

Figure 2 is a rear elevational view of the handwheel;

Figure 3 is a side elevational view; and

Figure 4 is a section on the line 4—4 of Figure 1.

We claim:

The ornamental design for a handwheel for a railway handbrake, as shown.
